UNITED STATES PATENT OFFICE.

JOHN RYAN STROUD, OF SCENERY HILL, PENNSYLVANIA.

SAFETY DEVICE FOR ELEVATORS.

1,386,170.

Specification of Letters Patent.

Patented Apr. 6, 1920.

Application filed October 25, 1919. Serial No. 333,330.

To all whom it may concern:

Be it known that I, JOHN R. STROUD, residing at Scenery Hill, in the county of Washington and State of Pennsylvania, a citizen of the United States, have invented or discovered certain new and useful Improvements in Safety Devices for Elevators, of which improvement the following is a specification.

10 My invention relates to improvements in safety stops for elevator cars. It is not so limited, but it finds immediate application in the elevators or hoists used in mines, and it will further be understood in reading the ensuing specification that it is applicable equally to elevators moving on an incline, as well as to those moving vertically.

The accompanying drawings illustrate my invention. Figure I is a fragmentary view 20 in side elevation of a car with my safety device applied to it. In this figure parts of the safety device are shown in cross section. Fig. II is a view in cross section through the guideway, showing the car with its safety device in plan. Fig. III is a vertical section through the car on the line indicated at 3—3, Fig. II. And Fig. IV is a side elevation at right angles to the showing of Fig. I.

30 The elevator car or cage shown diagrammatically is indicated at 1, and requires no particular description. On either side of this car or cage, extending longitudinally in the direction of cage travel and adjacent 35 the cage, are posts 2. These are coöperating parts, as will presently appear, for the safety device. They may also serve (and ordinarily such is the case) as guideways for the car. Mounted upon the car in suitable 40 bearings is a pair of shafts 3, and each of these shafts carries at either end and rotatable upon it, a cam 4. These cams on the range of rotation recede from and come into contact with the posts 2. They are 45 arranged pair by pair on opposite sides of each post, and as they come to post-engaging position, each pair forms a clamp upon the post.

Suitably mounted upon the car are motor 50 members, conveniently taking the form of expansion springs 5, one for each cam, and these springs operate as they expand, through suitable gearing, to swing the cams from inactive to post-engaging position.

55 As shown in the drawings, this connection

consists in each case of a pivoted beam or bar 6, provided with an arc of a gear-wheel 7, which arc meshes with a pinion face 8, formed integral with cam 4. It will be seen that the beam 6 with its pinion arc 7 is but a portion of a complete pinion, and indeed, as will readily be understood, a complete pinion might be employed, if it were convenient so to do.

Each shaft 3, at the point where the cams are mounted upon them, is cut away to form semi-circumferential slots 9, and the cam members 4 are provided each with a pin 10 entering the slot. It will thus be seen that each cam has a range of rotation upon the shaft of 180° (the exact amount is unimportant), and that the abutment of the pin against the end of the slot prevents rotation.

Each shaft 3 is further provided at a suitable point (conveniently midway of its length) with a pinion 11 (cf. Fig. IV) and each pinion 11 is engaged by a rack 12, and accordingly as rack 12 moves through its range of permissible motion from one extremity to another, so the shafts 3 will be turned. The parts are so proportioned and arranged that as the racks assume the alternate extreme positions shown in full and in dotted lines respectively in Fig. III, the shafts stand either in the position shown in Fig. I, with the grooves 9 beneath, or in a position 180° removed from that, with the grooves 9 uppermost.

Referring now to Fig. III, the suspension 90 of car 1 by car-sustaining cable 13 will be apparent. It is effected through the link 14 which engages the car through a compression spring 15. In case the car-sustaining cable breaks, the spring 15, expanding, 95 causes the link to move relatively to the car from the position indicated in full lines Fig. III, to the dotted-line position. It will further be observed from Fig. III that the racks 12 are connected to link 14, the arrangement being such that, in the event of parting of the cable, the expansion of spring 15, moving link 14 in the manner indicated, will drive the racks 12 from one limit of intended motion to the other, and 105 in so doing effect a corresponding turning of the shafts 3. The extent of turning so effected has already been indicated.

It remains only to note that, comparing Figs. I and III, so long as the car is hung 110

by the car-sustaining cable 13, the cams remain in the position shown. In that position the tension of springs 5, exerted through the gear connection 7 and 8, hold the cams 5 4 in the position shown, the pins 10 abutting against the ends of the slots 9. The shafts 3 are held immovable by the weight of the car in fixed position respecting racks 12. This abutment of the pins 10 against the 10 ends of slots 9 is effective to prevent expansion of springs 5, so long as the car is sustained by its cable. It is apparent that it is the weight of the car, acting through these instrumentalities, that holds both 15 spring 15 and springs 5 compressed and under tension. In case the car-sustaining cable parts, immediately these things happen: link 14 moves downwardly, carrying racks 12; shafts 3 are rotated until grooves 20 9 are uppermost; springs 5 are then free to expand. In expanding they swing beams 6 and, through the gearing 7, 8, cause cams 4 to turn until the cam faces come into bearing upon posts 2 and, inasmuch as there are 25 two of these clamping members acting as a pair on opposite sides of each post, a clamping such as to arrest the falling of the car is effected.

It remains to note certain characteristics 30 of this safety device. First of all, it is to be observed that each cam is driven independently of the others. In the form shown each has its own motor, namely, an expansion spring 5. When once the shafts 3 have 35 turned under the conditions and in the manner explained, each cam, separately driven, is free to move through its whole range of motion, or so much thereof as is requisite to bringing its acting face in contact with the post. This is a feature of great advantage; for, where such post-engaging cams 40 are mounted so that they are mechanically coupled together to act in pairs or in sets, there is no provision made to overcome defective engagement of a post, in case the 45 car happens to occupy an asymmetrical position. It is not uncommon for a car to become slightly twisted in its runway, and then one of a pair of post-engaging cams 50 may be very much nearer the face of its post than the other, and where there are four cams, two may be quite near to and two quite remote from post engagement. Furthermore, these posts wear away, and are 55 apt to have irregularities of surface, so that there are accidental variations of distance between cam and post. When cams are harnessed to act in pairs or in sets of four, the safety device may be ineffective or 60 faultily effective, by reason of the fact that some only of the cams take purchase upon the face of the post. But by my invention, in which each cam is unrestrained by any other and is free to move under its impelling 65 force until it makes contact with the face

of the post, a sure engagement is provided for.

Another feature of advantage is this. Having, as I show, and as I preferably employ, a separate expansion spring for 70 each cam, I may make those springs as heavy as I will, and I may thus insure, not merely force enough to bring the cam into contact with the surface of the post, but I may have a sufficient store of force to drive 75 the cam against the surface of the post, and back it with force sufficient to insure that it will bite upon the surface.

I have in the foregoing specification intimated the possibilities of various modifications and details of structure, and it will be understood that I do not mean to confine myself in respect to such details.

I claim as my invention:

1. A safety device for elevators including, in combination with a traveling car hung by a cable, a post extending adjacent the car and in the direction of car travel, two shafts borne by said car and rotatable in suitable bearings, means operated on the parting of the car-sustaining cable for turning said shafts, a pair of post-engaging cams borne one by each of said shafts and capable of limited rotation thereon, and means for rotating each cam upon its shaft 95 independently of the other, substantially as described.

2. A safety device for elevators including, in combination with a traveling car hung by a cable, a post extending adjacent 100 the car and in the direction of car travel, two shafts borne by the car and rotatable in suitable bearings, means operated on the parting of the cable for rotating said shafts, a pair of post-engaging cams borne one by 105 each of said shafts and rotatable thereon within predetermined limits, a pair of tension springs, and two sets of gearing operated severally by said springs and operating severally said cams, substantially as described.

3. A safety device for elevators including, in combination with a traveling car hung by a cable, a post extending adjacent the car and in the direction of car travel, 115 two shafts borne by the car and rotatable in suitable bearings, a pinion keyed to each of said shafts, a rack engaging each of said pinions, means for shifting said racks on the parting of the car-sustaining cable, a 120 pair of post-engaging cams borne one by each of said shafts and capable of limited rotation thereon, and means for rotating each cam upon its shaft independently of the other, substantially as described.

4. A safety device for elevators including, in combination with a car sustained by a cable, a post extending adjacent the path of car travel, two intermeshing pinion members borne by said car, a motor member con- 130

stantly exerting a turning tendency upon one of said pinion members, a movable post-engaging cam borne to post-engaging position through the turning of the other of 5 said pinion members, a member movable to and from engagement with the second of said pinion members, held to such engagement by the weight of the car when sustained by its cable, and when so held over- 10 coming the tendency of said motor member to turn said pinion members and bring said cam to post-engaging position, and means effective on the parting of the car-sustaining cable for moving the member last named 15 from the engagement defined, substantially as described.

5. A safety device for elevators including, in combination with a car sustained by a cable and a post extending adjacent the 20 path of car travel, a shaft rotatable in its mountings in said car and having a slot in its surface partly encircling it, a pinion with a cam face rotatable upon said shaft and provided with a pin entering said slot, and 25 means for bringing the said shaft to one or the other of two alternate positions of rotation accordingly as the car is sustained by its cable or released, and means tending

constantly to rotate the cam upon said shaft, substantially as described. 30

6. A safety device for elevators including, in combination with a car sustained by a cable, a post extending adjacent the path of car travel, two pairs of intermeshing pinion members borne by said car, a 35 motor member constantly exerting a turning tendency upon one of the pinion members of each pair, a pair of movable post-engaging cams borne to post-engaging position through the turning of the other members of the pair of pinions, and members 40 movable to and from engagement with the second-mentioned pinions of the pair, held to such engagement by the weight of the car when sustained by its cable, and when 45 so held overcoming the tendency of said motor members to turn said pinion members and bring said cams to post-engaging position, substantially as described.

In testimony whereof I have hereunto 50 set my hand.

JOHN RYAN STROUD.
